UNITED STATES PATENT OFFICE.

EVA C. STUVER, OF TACOMA, WASHINGTON.

DESIGN FOR A BABY-SPOON.

43,208.

Specification for Design.

Patented Oct. 29, 1912.

Application filed February 5, 1912. Serial No. 675,677. Term of patent 14 years.

To all whom it may concern:

Be it known that I, EVA C. STUVER, a citizen of the United States, residing at Tacoma, in the county of Pierce and State of Washington, have invented a new, original, and ornamental Design for a Baby-Spoon, of which the following is a specification, reference being had to the accompanying drawing, forming part thereof.

The figure is a perspective view showing my new design.

I claim:

The ornamental design for a baby spoon, as shown.

In testimony whereof, I affix my signature, in presence of two witnesses.

EVA C. STUVER.

Witnesses:

S. T. STUVER,
JOHN CANNON.
